UNITED STATES PATENT OFFICE.

EDWIN E. HUTSHING, OF SEATTLE, WASHINGTON.

PHONOGRAPH CABINET.

1,426,568.

Specification of Letters Patent. Patented Aug. 22, 1922.

Application filed May 10, 1920. Serial No. 380,085.

To all whom it may concern:

Be it known that I, EDWIN E. HUTSHING, a citizen of the United States of America, and resident of the city of Seattle, in the 5 county of King and State of Washington, have invented certain new and useful Improvements in Phonograph Cabinets, of which the following is a specification.

My invention consists of a phonograph 10 cabinet which better adapts it to the holding of the records so as to make them easily and quickly accessible.

One object of my invention is to promote accessibility of the records and ease in filing 15 and removing phonograph records.

Another object is to provide a convenient arrangement of the motor, shaft, turntable and horn within the same cabinet.

Summed up, my general object is to produce 20 a phonograph and cabinet so arranged that the record-storing space is readily accessible, and so that the records therein are both conveniently and compactly stored.

The features of my invention which I 25 consider new, will be first described and that which I consider novel and upon which I desire to obtain patent will then be particularly defined by the claims.

The accompanying drawings illustrate my 30 invention in the form of construction which I prefer to employ.

Figure 1 is a vertical section taken from front to rear through the center of the cabinet.

35 Figure 2 is a half plan view and a half section taken through the central plane of the lower record containers.

Figure 3 is an enlarged view of one of the containers and their supporting ring.

40 Figure 4 is a modified form of the supporting arm.

My device is provided with a suitable cabinet as 1, which may, in the main, be of any suitable construction. The front 45 side of the cabinet has a door or doors 2, which give access to its interior wherein is contained the record-storing means.

I have provided a sleeve 3 which is located centrally with respect to the cabinet 50 and which is secured in position in any suitable manner, as by flanges 30 which are secured to shelves 10 and 11. The said sleeve has a number of rotatable disks 31 having holes 33 distributed adjacent their 55 edges and so spaced as to receive the downwardly bent ends of horizontal outwardly

extending arms 32, carried by the individual record holders 34. The disks 31 may be held in position by collars 5 which are secured to the sleeve 3 in any suitable manner. The arms are pivoted in holes 33 in the disks 31.

The arms 32 are preferably of a U type, so as to receive individual record-storing envelopes as 34. A suitable brace or connecting member 35 is made preferably of a U type and split at the end so as to form flanges on arms 32 and fastened thereon in any suitable manner. This forms an inward stop for the envelope 34 and record 4 70 therein.

I prefer to use envelopes made of a heavy paper or cardboard, and cut away the center 37 on each side of the envelope, so that the reading matter on the central portion 75 of the record 4 may be easily read without pulling the record out. I have cut away another portion 38 of my envelope 34 so as to conveniently remove the record 4.

It is desired to form a stop 39 at the 80 lower front or outward portion of the envelope 34 by securing the two edges together, by gumming them together, or by using a strip of any suitable material about the two outer sides of said envelope so that 85 the record 4 cannot roll in an outward direction when the door 2 is opened or when the envelope is rotated.

A motor 6 is secured on the bottom side of the shelf 11 so that the drive shaft 7 90 will occupy a central vertical position in the sleeve 3. The shaft 7 is connected to the motor 6 in any suitable manner. The upper end of the shaft 7 is connected with a turntable 8.

A stop 81 is provided which is of a type well known in phonographs. A speed regulator is indicated, this being controlled by a shaft 82 having a controlling arm 83 and a rod 84 connected with the motor. 95

The tone-arm 9 may be made of such a construction as to allow the horn 91 to connect with it at the position shown in Figures 1 and 2. The section 91 of the horn is located at a corner of the cabinet so as 105 to not interfere with the turning of the record holding device and passes through shelves 10 and 11 to the amplifying horn 92 which is located at the bottom of the cabinet between the shelves 11 and 12. The amplifier 110 horn is made in any suitable manner so long as it substantially clears the motor 6.

I desire to wind my motor from the usual location and in so doing I lengthen my winding shaft 61 to the outer casing 1 and mount a sprocket 62 on the said shaft. 5 Another sprocket 63 mounted at the desired height and a suitable chain 64 connects the two sprockets. A suitable winding arm 65 is connected to the upper sprocket 63. Suitable bearings are used to secure the said 10 parts together.

Figure 4 shows a modification in the construction of my supporting arms 32. I may desire to use rods 32' of a suitable size and strength and placed in a similar manner as 15 arms 32.

I desire holes punched in my envelope 34' so that the said envelope may be slid on the rods 32' and secured thereon in any suitable manner.

20 It may be seen from the above description that I have provided a phonograph cabinet wherein the record-storing space being positioned above the motor and amplifying horn, is up where it is easily accessible to the user, 25 without the necessity for stooping. All records are quickly accessible, and the titles may be read without removing the records from the envelopes.

What I claim as my invention is:

1. A disk record storing means comprising 30 a pair of vertically-spaced, laterally-extending arms, supports for the inner ends thereof, a vertical brace rigidly secured to each of said arms adjacent its inner end, and an envelope supported upon said arms, 35 and having its opening along the vertical side opposite said brace, the edges of said opening being joined slightly above the lowermost edge of the envelope.

2. A disk record storing means comprising 40 a pair of vertically-spaced, laterally-extending channeled arms, supports for the inner ends thereof, a vertical channeled brace rigidly secured to each of said arms adjacent its inner end, the channels in said 45 arms and brace being alined, and all facing the space included between the arms and brace, and an envelope received in said channels, and having its opening along the vertical side opposite said brace and having 50 means to prevent a record rolling therefrom.

Signed at Seattle, Washington this 1st day of May 1920.

EDWIN E. HUTSHING.
